US0D1028596S

(12) **United States Design Patent** (10) **Patent No.:** **US D1,028,596 S**
(45) **Date of Patent:** **** May 28, 2024**

(54) **WALL MOUNTED BOTTLE FILLER**

- (71) Applicant: **GLOBAL INDUSTRIAL DISTRIBUTION INC.**, Port Washington, NY (US)
- (72) Inventors: **Richard B. Leeds**, Port Washington, NY (US); **Bruce Zutler**, Port Washington, NY (US); **Phillip Lee**, Port Washington, NY (US)
- (73) Assignee: **GLOBAL INDUSTRIAL DISTRIBUTION INC.**, Port Washington, NY (US)
- (**) Term: **15 Years**
- (21) Appl. No.: **29/774,572**
- (22) Filed: **Mar. 17, 2021**
- (51) LOC (14) Cl. **20-01**
- (52) U.S. Cl.
USPC **D7/304; D7/397**
- (58) **Field of Classification Search**
USPC D7/300, 304, 305, 311–313; D23/201, D23/207, 209; D30/132, 133
CPC B67D 1/0014; B67D 1/16; B67D 3/009; B67D 7/42; B67D 7/421; B67D 2210/00031

(57) **CLAIM**

The ornamental design for a wall mounted bottle filler, substantially shown and described herein.

DESCRIPTION

FIG. 1 is a left front perspective view of a wall mounted bottle filler showing our new design;

FIG. 2 is a front view of the wall mounted bottle filler of FIG. 1;

FIG. 3 is a rear view of the wall mounted bottle filler of FIG. 1;

FIG. 4 is a left view of the wall mounted bottle filler of FIG. 1;

FIG. 5 is a right view of the wall mounted bottle filler of FIG. 1;

FIG. 6 is a top view of the wall mounted bottle filler of FIG. 1; and,

FIG. 7 is a bottom view of the wall mounted bottle filler of FIG. 1.

The broken lines in these drawings illustrate environmental features only and form no part of the claimed design.

1 Claim, 7 Drawing Sheets
